AUTOMATIC TRANSMISSION ANALYSIS UNIT

Robert Morgan, Conshohocken, Pa., Oscar McCabe, Lindenwold, N.J., and Michael Ratz, Philadelphia, Pa., assignors to Aamco Automatic Transmissions, Inc., King of Prussia, Pa., a corporation of Pennsylvania

Filed Mar. 26, 1969, Ser. No. 16,448

Term of patent 14 years

Int. Cl. D10—11

U.S. Cl. D52—6

FIG. 1

FIG. 2

FIG. 4

FIG. 3

FIG. 5

FIG. 1 is a front elevation of an automatic transmission analysis unit showing our new design;

FIG. 2 is a side elevation view;

FIG. 3 is a side elevation view showing the side opposite the view in FIG. 2;

FIG. 4 is a rear elevation view; and

FIG. 5 is a top plan view.

We claim:

The ornamental design for an automatic transmission analysis unit, substantially as shown and described.
